MAIL-FEEDING MECHANISM.

1,293,260.

Specification of Letters Patent.

Patented Feb. 4, 1919.

Original application filed July 5, 1917, Serial No. 178,833. Divided and this application filed May 18, 1918.
Serial No. 235,379.

To all whom it may concern:

Be it known that I, MAXIMILIAN G. VOIGTLANDER, a citizen of the United States, residing at Cincinnati, in the county of Hamilton and State of Ohio, have invented certain new and useful Improvements in Mail-Feeding Mechanism, of which the following is a specification.

The present application is a division of 10 my application for patent on improvements in mail distributing devices, filed July 5, 1917, Serial No. 178,833, which exemplifies a device in which the present invention is employable and to which reference is hereby made.

It is the object of my invention to provide novel means for initiating the movement of pieces of mail to be distributed; further, to provide novel means for separately feeding the respective pieces of mail; and, further, to provide novel means for separately projecting pieces of mail in the feeding movement and retarding the balance of the pieces of mail to insure separate 25 projection of the several pieces of mail.

The invention will be further readily understood from the following description and claims, and from the drawings, in which latter:

30 Figure 1 is a plan view of my improved device, shown in connection with only so much of a mail distributing mechanism as is necessary to illustrate my invention.

Fig. 2 is a front elevation of the same.

35 Fig. 3 is a bottom view of the same.

Fig. 4 is a diagrammatic representation of the electrical connections.

Fig. 5 is a side elevation of a switch for forming the electric circuit.

40 Fig. 6 is a vertical cross-section of the same, taken on the line 6—6 of Fig. 5; and,

Fig. 7 is a detail in vertical cross-section, taken on the line 7—7 of Fig. 2, showing the driving gearing.

45 I have shown, described and claimed the electric connections and devices in conjunction therewith in my aforesaid application heretofore filed and do not therefore herein claim the same.

50 My invention is employable where it is desired to project or feed pieces of mail

separately for distribution, for instance, in a device shown, described and claimed in my aforesaid application heretofore filed.

My invention contemplates a manually operated electric control for initiating movements of the separate pieces of mail; projecting the same into conveying mechanism for conveyance thereof to a mail compartment or compartments, and retarding means acting on the pieces of mail to insure that but one piece of mail is projected and fed at the same time.

The pieces of mail are instanced as moving in the direction of arrow *a* (Fig. 1), toward the mail compartment or compartments, not shown, and are arranged to follow one another. The respective pieces of mail travel consecutively.

The mail, preferably as it comes from the canceling machine, is received in a receptacle 11, (see Figs. 1, 2 and 3), wherein it is set on edge, one piece of mail in rear of the other, and normally pressed toward the delivering end 12 of the receptacle, as by means of a slide 13 slidable on rods 14 which form the bottom of the receptacle and are urged toward the delivering end by means of a weight 15 on a flexible connection 16 received over a directing pulley 17 and attached to the slide.

Each piece of mail, instanced at 18, (Fig. 2), as it arrives at the delivering end of the receptacle, has its address, exemplified at *b*, exposed by the exposure opening 21, preferably filled by a transparent plate 22, as of glass, and has a quick thrust movement or impulse imparted thereto by the operator, whose position is at the key-board 23, the respective keys 24 of the key-board controlling the initiation of travel, so that the feeding impulse may be imparted to the piece of mail whose address is exposed by the exposure opening, regardless of which key is pressed.

I have, in Fig. 4, shown a diagrammatic representation of the electric circuit for controlling this initiation of travel by one of the keys, as will be hereinafter explained, the controlling mechanism for the respective keys being preferably duplicates of this mechanism, in so far as imparting feeding

impulse to the respective pieces of mail is concerned, the construction of each key and its connected mechanism being shown in Figs. 5 and 6.

- 5 The initiation of travel of the piece of mail, whose address is exposed at the exposure opening in front of the operator, is caused by a motion initiating roller 27. The roller 27 preferably has knobs 28 thereon, 10 for instance of rubber or other material making ready frictional contact with the piece of mail exposed for delivery, for imparting the desired quick motion or impulse thereto.
- 15 Roller 27 normally moves in the direction of the arrow *c* (Fig. 1). A retarding roller 29 rotates in a direction so that that portion of its periphery which contacts the mail moves opposite to the direction of movement 20 of the mail contacting portion of the periphery of the roller 27, and is arranged to retard all other than the one piece of mail at the forward end of the stack of mail contacted by the roller 27 and intended at the 25 moment for delivery. The retarding roller acts to push back into the receptacle any piece of mail which has a tendency to adhere to or move with the one piece of mail being delivered.
- 30 The piece of mail being delivered is next preferably engaged by a follow-up feeding roller 31, which rotates in the same direction and at the same side of the path of the mail as the roller 27, and preferably engages the 35 piece of mail prior to release thereof by the roller 27 for continuing the thrust movement of the same toward the conveyer. The rollers preferably continuously rotate.

- 36 The roller 27 is fixed to a shaft 36 rotated 40 in a bearing 37 of an arm 38 pivoted by a bearing 39 about a depending bearing-sleeve 40 of a bracket-frame 41 fixed to the main frame of the machine. A spring 42, the respective ends of which are secured to the 45 arm and to the bracket-frame, normally resiliently urges the roller 27 away from contact with the mail.

- 46 As soon as the operator desires to project or feed a piece of exposed mail, he presses 50 one of the keys 24 of the keyboard. The depression of the key, in the present instance, energizes an electro-magnet 45, the coil or coils of which are preferably fixed to the bracket-frame 41, and the armature 46 of 55 which is preferably fixed to the arm 38, so that when the key is operated, the armature is momentarily attracted toward the coil and the motion-initiating roller 27 momentarily makes contact with the forward or 60 exposed piece of mail for initiating its movement with a sharp thrust.

- 65 A conveyer, instanced as comprising a pair of belts 49, travels laterally for aiding in carrying the piece of mail to its destination, for instance a given one of a series of

compartments arranged to selectively receive the respective pieces of mail, as explained in my aforesaid application.

The belts are caused to move by being received about pulleys at the respective ends 70 of the loops thereof, the driving pulley 51 being shown. The mail-contacting stretches of the belt move in the direction of the arrow *a*, (Fig. 1). The pulley 51 is fixed to an upright shaft 52. This shaft rotates in 75 a bearing 53 of the bracket-frame and has a bevel-gear 54 secured thereto. (See Figs. 1, 2 and 3). A bevel pinion 55 meshes with the bevel-gear and is fixed to a shaft 56 journaled in bearings 57, 58, and has a gear 80 59 fixed thereto. A drive-shaft 61 is suitably driven, as by means of a pulley 62 thereon, receiving a suitable belt 63 thereover from a usual electric motor 64, which may be suitably supported on the frame of 85 the machine. The drive-shaft has a gear 66 thereon which meshes with a transmitting gear 67 meshing with the gear 59.

A gear 71 is fixed to the pulley-shaft 52 and meshes with a transmitting gear 72, 90 which meshes with a gear 73 on a shaft 74, journaled in the bearing-sleeve 40. The follow-up roller 31 is fixed to this shaft. The gear 73 meshes with the transmitting gear 76, which meshes with a gear 77 on the shaft 95 36, for rotating the motion initiating roller 27. The retarding roller 29 is rotated by a train of gears 81, 82, 83, 84. The gear 81 meshes with the gear 73 and the gear 84 is fixed to a shaft 85 to which the retarding 100 roller 29 is secured.

The pieces of mail are arranged to move in a channel 88, instanced as having a bottom 89 and side walls 90, 91. The side walls are connected by suitable yokes 92 received 105 over the channel 88 for permitting the pieces of mail to pass thereunder. The side wall 90 is preferably extended upwardly for forming a backing support for the propelling stretch of the endless belt. The belts 110 pass through apertures 93 in the side wall 91. The side wall 90 is provided with a rearward extension 95, at the receiving end thereof, forming a wall for the receptacle 111. The rollers 27, 29, 31, project through slots 97, 98, 99, in the respective side walls. A suitable number of rollers 101, instanced as idler rollers, may be provided for aiding in feeding the pieces of mail. The idler roller shown, is mounted on a shaft 102 in 120 a lever 103 pivoted at 104 to a bracket 105 extending from the side wall 90, and spring-pressed toward the belt by a spring 106 located between the heel 107 of the lever and the bracket, so as to contact the piece of mail 125 and urge the same toward the conveyer belts.

Any one of the keys 24 controls the electric current in the electric translating device 45. I have diagrammatically repre- 130

sented a desirable electric circuit for the electric translating device in Fig. 4, and in Figs. 5 and 6 I have exemplified a desirable form of electric contact means for the key.

111 represents a battery with which the leads for the key mechanism are connected. An electric conductor 112 leads from one of the poles of the battery and is electrically connected with a contact 113 for the key. A coacting contact 114 is provided. An arm 115 has an electric contact 116 thereon arranged to bridge the contacts 113, 114. The contact 116 is located on and moves with the arm 115 but is insulated therefrom by insulation 117.

The arm 115 is pivoted at 120 to lugs 121 of the frame of the key-board, a spring 122 normally raising the arm, so that the contact thereon is normally out of contact with its coacting contacts. An electric conductor 124 leads from the other pole of the battery to one of the terminals of the coil of the electro-magnet 45, which controls the armature 46 for the movement-initiating roller 27, for initiating movement of the mail. An electric conductor 125 connects with the other terminal of said electro-magnet and is electrically connected with the electric contact 114, so that said electro-magnet is energized by closing the gap between the contacts 113, 114, by means of the electric contact 116, so that the roller 27 is moved toward the mail at each actuation of the key.

The contact of the contact 116 with the contacts 113, 114, is preferably only momentary for causing operation of the motion initiation roller 27 on the piece of mail only sufficiently long to initiate movement of said piece of mail sufficiently to cause its being received by the next motion imparting means.

For aiding in this result, I provide the key-bar 128 with an operating finger 129, pivoted to the key-bar at 130 and arranged to contact the end of the switch-arm 115 and move the latter for a given distance, whereupon the finger drops away from the switch-arm for causing retraction of said arm by means of the spring 122. In order to give a wide range of movement to the arm, I have provided the finger with an extension 131 having a slot 132 therein, a pin 133 being received in the slot and controlling the direction and movement of the finger. The pin 133 is in an upright 134 which carries a bearing 135 for the key-bar.

60 The key-bar is received through an aperture 138 in a supporting plate 139 of the key-board mechanism, and is normally retracted by a spring 140, a pin 141 limiting retractive movement of the key-bar. The contacts 113, 114, are insulated from the

supporting plate by a sheet 142 of insulation. When the key-bar is retracted by the spring 140, the operating finger 129 will repass the arm 115 for being located thereabove ready for a subsequent depression of 70 said arm at the next depression of the key-bar.

Having thus fully described my invention, what I claim as new and desire to secure by Letters Patent, is:

75 1. In a mail distributing mechanism, the combination of a mail receptacle, mail conveying means coacting therewith, and means projecting mail into said conveying means comprising a mail projecting roller, a mail retarding part coacting with said mail projecting roller, and means selectively holding said mail projecting roller in inactive relation with the mail and momentarily moving said mail projecting roller into contact with the piece of mail exposed thereto, said last-named means including an electric translating device.

80 2. In a mail distributing mechanism, the combination of a mail receptacle, mail conveying means therefor, and means projecting mail into said conveying means comprising a normally continuously rotating mail projecting roller, a mail retarding part coacting with said mail projecting roller, 90 and means for alternately moving said mail projecting roller into active relation and into inactive relation with the mail including resilient means for moving said mail projecting roller in one direction and electric means to move said mail projecting roller in the opposite direction for causing alternate momentary contact of said mail projecting roller with the piece of mail exposed thereto and idle relation of said mail 95 projecting roller.

100 3. In a mail distributing mechanism, the combination of a mail receptacle, mail conveying means thereof and means projecting mail into said conveying means comprising a normally continuously rotating mail projecting roller, a mail retarding part coacting with said mail projecting roller, means for alternately moving said mail projecting roller into active relation 110 and into inactive relation with the mail including an electric translating device to move said mail projecting roller, whereby to cause alternate momentary contact of said mail projecting roller with the piece 115 of mail exposed thereto and idle relation of said mail projecting roller, and a propelling roller between said mail retarding part and said mail conveying means.

120 4. In a mail distributing mechanism, the combination of a mail receptacle, mail conveying means coacting therewith and means projecting mail into said conveying means comprising a normally continuously rotating mail projecting roller, a normally con- 125

tinuously rotating mail retarding roller co-
acting with said first-named roller, means
normally resiliently holding said mail pro-
jecting roller in inactive relation with the
5 mail, and electric means acting to momen-
tarily move said mail projecting roller into
contact with the piece of mail exposed
thereto.

5. In a mail distributing mechanism, the
10 combination of a mail receptacle, mail con-
veying means therefor, and means project-
ing mail into said conveying means com-
prising a normally continuously rotating mail
15 projecting roller, a normally continuously
rotating mail retarding roller coacting with
said first-named roller, means normally resili-
ently holding said mail projecting roller in
inactive relation with the mail, electric means
20 acting to momentarily move said mail pro-
jecting roller into contact with the piece of
mail exposed thereto, and a propelling roller
between said retarding roller and said mail
conveying means.

6. In a mail distributing mechanism, the
25 combination of a mail receptacle arranged
for receiving mail to be distributed, said mail
receptacle having an exposure opening for
exposing the addresses on the pieces of mail,
means for normally urging the pieces of mail
30 toward said exposure opening, a normally
rotating propulsion roller, means resiliently
urging said propulsion roller to position
with relation to the pieces of mail, electric
means for moving said propulsion roller in
35 opposite direction, mechanism comprising a
key, and means coacting with said key for
controlling the electric circuit in said elec-
tric means.

7. In a mail distributing mechanism, the
40 combination of a mail receptacle arranged
for receiving mail to be distributed, said mail
receptacle having an exposure opening for ex-
posing the addresses on the pieces of mail,
means for normally urging the pieces of mail
45 toward said exposure opening, a normally
rotating propulsion roller, means resiliently
urging said propulsion roller to inactive re-
lation with the pieces of mail, electric means
for normally moving said propulsion roller
50 into active relation with the piece of mail ex-
posed at said exposure opening, mechanism
comprising keys, means coacting with said

respective keys for causing electric circuit in
said electric means for moving said propul-
sion roller into said active relation, and a re-
tarding roller coacting with said propulsion
55 roller for retarding pieces of mail free of
contact by said propulsion roller.

8. In a mail distributing mechanism, the
60 combination of a mail receptacle arranged
for receiving mail to be distributed, said
mail receptacle having an exposure opening
for exposing the addresses on the pieces of
mail, means for normally urging the pieces
65 of mail toward said exposure opening, a nor-
mally rotating propulsion roller, means resili-
ently urging said propulsion roller to po-
sition with relation to the pieces of mail, elec-
tric means for moving said propulsion roller
70 in opposite direction, mechanism comprising
keys, means coacting with said respective
keys for controlling the electric circuit in
said electric means whereby to move said
propulsion roller into active relation with
75 the mail, a second roller acting on the respec-
tive pieces of mail, and a retarding roller co-
acting with said propulsion roller located be-
tween said propulsion roller and said sec-
ond roller, acting on the sides of the pieces
80 of mail opposite to the latter.

9. In a mail distributing mechanism, the
combination of a mail receptacle having an
exposure opening, means for normally urg-
ing the pieces of mail toward said exposure
opening, a normally rotating propulsion 85
roller for the pieces of mail normally in in-
active relation with the pieces of mail, an
electric translating device acting on said pro-
pulsion roller to position the same, mecha-
nism comprising a key-board, and an electric
90 circuit for said electric translating device,
the keys of said key-board respectively com-
prising means affecting said electric circuit
whereby said electric translating device is
95 caused to act for movement of said propul-
sion roller toward the exposed piece of mail
for propelling the same.

In testimony whereof, I have hereunto
signed my name in the presence of two sub-
scribing witnesses.
